(57) **CLAIM**

The ornamental design for a urine collection apparatus
container lid, as shown and described.

DESCRIPTION

FIG. 1 is a front, top, perspective view of a urine collection
apparatus container lid, according to a first embodiment of
a new design;

FIG. 2 is a rear elevational view thereof;

FIG. 3 is a right side elevational view thereof;

FIG. 4 is a front elevational view thereof;

FIG. 5 is a left side elevational view thereof;

FIG. 6 is a top plan view thereof;

FIG. 7 is a bottom plan view thereof;

FIG. 8 is a bottom perspective view thereof; and,

FIG. 9 is a front, top, perspective view of the urine collection
apparatus container lid shown in FIGS. 1-8 in its environ-
ment assembled with a container.

(Continued)

The dashed lines in the FIGS. 1-8 illustrate the portions of the design that form no part of the claimed design. The dash dot lines in FIG. 9 depict environmental subject matter only and form no part of the claimed design. None of the broken lines form any part of the claimed design.

1 Claim, 6 Drawing Sheets
